UNITED STATES PATENT OFFICE.

FRANK PILLEY, OF KANSAS CITY, MISSOURI.

CAN UP-ENDING MECHANISM.

1,366,933.

Specification of Letters Patent.

Patented Feb. 1, 1921.

Application filed June 11, 1919. Serial No. 303,411.

To all whom it may concern:

Be it known that I, FRANK PILLEY, a citizen of the United States, residing at Kansas City, in the county of Jackson and State of Missouri, have invented certain new and useful Improvements in Can Up-Ending Mechanism; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

This invention relates to up-ending mechanism for containers and it is particularly applicable for use in connection with milk can cleaning apparatus.

Milk cans are generally cleaned by being passed in inverted position along a way so that the interior may be subjected to the action of hot water, steam or some suitable sterilizing means. They are then discharged to be deposited upon a runway down which they may gravitate to a collecting platform or base.

I have provided means whereby the inverted cans may be up-ended between the point of discharge from the can cleaning apparatus or machine and the runway and I have arranged the up-ending mechanism so that it may be actuated in synchronism with certain elements of the can cleaning mechanism so that the movement of the up-ending element will be timed with the discharge of the can from the can washing machine.

The invention contemplates the provision of means for receiving an inverted can and for positively up-ending it so that its bottom will rest upon an inclined way or receiving platform and it is the purpose of the invention to accomplish this without denting the can.

Other objects and advantages of the invention will be apparent hereinafter by reference to the description in connection with the accompanying drawings, in which—

Figure I is a perspective view of an up-ending device constructed in accordance with my invention.

Fig. II is a side elevational view of the same showing the basket in can-receiving position.

Fig. III is a side elevational view of my

invention showing the basket in can-discharging position.

Fig. IV is a fragmentary view of a rest bar, and

Fig. V is a cross sectional view through the basket showing a buffer roller in elevation.

Referring now to the drawings by numerals of reference:

1 designates a can cleaning machine of approved construction, here shown as being provided with a can guideway 2 and a can top guideway 3, the tops 4 being shown as secured to the cans 5 by coupling wires 6. In the side of the can cleaning machine is a slot 7 in which is mounted an oscillatory bar 8 pivoted at one end and engaged at the other end 9 by a reciprocating pitman 10, which may be driven by any suitable power. The bar 8 extends transversely of the machine and swings to and fro under the action of the pitman 10 to eject the cans and their covers.

The mechanism just described specifically forms no part of my invention as it is old and well known, as is also the gravity runway 11 provided with the rollers 12 down which the cans may gravitate.

By reference to Fig. I it will be observed that interposed between the runway 11 and the can washing machine is a can up-ending mechanism including a supporting frame 13 at the rear of which is journaled a rock shaft 14 carrying a swinging cradle or basket 15. The basket is shown as consisting of side bars 16 and 17 in the form of cranks rigidly secured upon the shaft 14 and the side bars 90 are connected by a web 18 of metal having a concave portion 19 and a flat portion 20. Extending forwardly of the basket and integral with the side bars 16 and 17 is a substantially V-shaped can tilting member 21, 95 the forward part of which, when the basket is in receiving position, is inclined downwardly, there being a transverse can lip engaging bar or rib 22 at the intersection of the angles so that when the can is discharged from the can washing machine, the lip of the can will strike against the bar 21 and throw it over into the concave portion 19, as best seen in Figs. I and II. Extending across the basket is a rod 23 which 100 carries a relatively soft rubber buffer roller 24 positioned at the forward end of the concave portion 19 so that when the cans are

thrown from a vertical to a horizontal position, they will strike against the roller 24 which will receive the impact of the blow and thereby prevent denting of the cans. 5 The rod 23 is vertically adjustable with end slots 25 and 26 carried by the forward portions of the arms 16 and 17, and said rod may be held in its adjusted position through the medium of the nuts 27 and 28 on the rod 23. The forward end of the swinging member, which includes the basket and the can-receiving portion, is adapted to rest upon a bar or yoke 29 adjustably secured to the top bars of the frame 13 by the 10 fastening devices 30 and 31. The bar 29 is adjustable to provide for different size cans, as is also the rod 23.

I have provided mechanism for swinging the cradle 15 in synchronism with the discharging mechanism of the can washing machine and this operating mechanism is shown in Figs. I, II and III as including a crank 32, normally depending from the shaft 14 and connected to a sectionally adjustable operating link 33, one end of which is pivoted to the crank 32 intermediate its ends and the other end of which is provided with a latch head 34 extending adjacent to the can advancing or discharging lever 8. 25 The lever 8 is provided with an upstanding lug or projection 35 adapted to engage a notch or projection 36 on the head 34 supported upon the rail 37 by the roller 38 but the head is adapted to be thrown out of engagement with the lug 35 when the cam face 39 of the head contacts with the inclined face 40 of the release cam 41, as will be presently explained.

The end 42 of the crank 32 is connected 40 to a piston rod 43 on one end of which is a piston 44 in a pivoted dash pot cylinder 45, the piston being free to move from left to right on account of the ports 46 but the movement in an opposite direction being resisted by the pressure between the piston and the head 47, which can only be relieved through the pet cock 48, the resistance to the piston 44 being controllable through said pet cock.

45 When the parts are assembled as illustrated in the drawings and the bar 8 moves from right to left to advance or eject a can, the can will be thrown upon the V-shaped can-receiving portion of the cradle so that 50 the lip will contact with the rib 22 whereby the inertia of the can will cause it to tilt over into the concave portion 19 of the basket. By this time the lug 35 will have ridden over the cam face 39 to engage the notch 36 and as the pitman 10 moves from left to right under the action of a crank or other appropriate device, the link 33 will move with it, swinging the arm 32 on shaft 14 so that an upward, rearward swinging 55 movement will be imparted to the cradle, as

indicated in Figs. II and III, so that the can will be carried to a vertical position and deposited upon the gravity runway 11 top side up. This movement will cause the end 39 of the link 33 to contact with the inclined face 70 40 of the release cam 41 so as to raise the head 34 out of engagement with the projection 35 and thereby permit the cradle to swing forward to the position shown in Fig. I. The forward swinging movement of the 75 cradle will be resisted, however, by the piston 44 in the cylinder 45 so that the cradle will come to rest upon the bar 29 gradually without liability of jarring the mechanism.

The cycle of operation just described will 80 be repeated as often as the cans are ejected from the can recleaning machine, the can up-ending movement of the cradle being relatively rapid and positively actuated through the bar 8 but the recovery being 85 relatively slow near the final position of rest on account of the dash pot consisting of the piston 44 and the cylinder 45.

From the foregoing description it will be 90 apparent that the mechanism may be readily operated from the power of a washing machine so as to operate in unison therewith and so that the cradle will be in position to receive the cans at each ejecting operation.

What I claim and desire to secure by 95 Letters-Patent is:

1. In a can up-ending machine, a rock shaft, a can up-ending means carried by the rock shaft, a crank connected to the rock shaft, means for positively actuating the 100 rock shaft in one direction, and means for yieldingly resisting its movement in the opposite direction.

2. In a can up-ending machine, a rock shaft, a can up-ending means carried by the 105 rock shaft comprising means for tilting the can and a basket to receive the can, and means for imparting a swinging movement to the rock shaft in one direction.

3. In a can up-ending machine, a rock 110 shaft, a can up-ending means carried by the rock shaft comprising means for tilting the can and a basket to receive the can, means for imparting a swinging movement to the rock shaft in one direction, and means 115 for yieldingly resisting movement of the rock shaft in the opposite direction.

4. In a can up-ending machine, a rock shaft, a cradle carried by the rock shaft, can overturning means carried by the cradle to 120 seat the can in said cradle and means for actuating the rock shaft.

5. In combination with a can washing machine in which the cans are progressively advanced through the machine, and a can 125 receiving means spaced therefrom, of a can up-ending mechanism between the two, comprising a cradle capable of swinging in the arc of a circle, can reversing means therein, and means for operating the cradle in syn- 130

chronism with the advancing mechanism of the washing machine.

6. In combination with a can washing machine in which mechanism is employed 5 to advance cans therethrough, a rock shaft, an upwardly swinging can up-ending member, one end of which is fixed to the rock shaft and means for actuating the rock shaft to swing the other end of the can up- 10 ending member in an arc generated from said rock shaft by the can advancing mechanism.

7. A can washing machine having can advancing mechanism, a can up-ending mechanism 15 at the discharge end of the washing machine, and comprising a swinging can-receiving member, a link for operating the swinging member, a notched head on the link, means moving with a part on the washing machine to engage the notch in the head 20 to impart movement to the link in one direction, and means for releasing the head upon completion of its movement in one direction.

25 8. A can washing machine having can advancing mechanism, a can up-ending mechanism at the discharge end of the washing machine, and comprising a swinging can-receiving member, a link for operating the 30 swinging member, a notched head on the link, means moving with a part on the washing machine to engage the notch in the head to impart movement to the link in one direction, means for releasing the head upon 35 completion of its movement in one direction, and yielding means for resisting movement of the can-receiving member in one direction.

9. A can up-ending mechanism comprising 40 ing a swinging can up-ending member hav-

ing a free end, a supporting bar for the free end and means for vertically adjusting said bar.

10. A can up-ending mechanism comprising 45 a swinging can up-ending member, a buffer thereon, and means for adjusting said buffer.

11. A can washing machine having a discharge end, an inclined gravity conveyer in line with the discharge end of the washing 50 machine and having its receiving end in the plane of the discharge end of the washing machine, and a swinging can-reversing device between the washing machine and the conveyer, said reversing device being piv- 55 oted at one end and having its opposite free end provided with means for tilting the cans to reversing position.

12. A can up-ending mechanism comprising 60 a rock shaft and means for operating a cradle carried by the shaft, comprising a can receiving basket at one end, an incline at the other end, and a can-lip-engaging-bar carried by the incline to upset the can 65 into the basket.

13. In combination with a can cleaning machine carrying a bar having intermittent backward and forward movement to advance the cans through the machine, and a can up-ending member, having an operating arm, of a link, one end of which is connected to said arm and the other having a hook adapted to be engaged by a lug on said bar to impart movement to said cradle, and a cam carried by the can cleaning 70 machine adapted to engage the hook to 75 free the hook from the lug.

In testimony whereof I affix my signature.

FRANK PILLEY.
